The ornamental design for a highlighter, as shown and described.

DESCRIPTION

FIG. 1 is an upper front right perspective view of a highlighter showing my new design;

FIG. 2 is an exploded lower front right perspective view thereof;

FIG. 3 is an upper front left perspective view thereof, with the cap removed and placed on the opposite end of the highlighter;

FIG. 4 is a top plan view of the highlighter shown in FIG. 1;

FIG. 5 is a bottom plan view thereof;

FIG. 6 is a right side elevation view thereof;

FIG. 7 is a front elevation view thereof;

FIG. 8 is a left side elevation view thereof; and,

FIG. 9 is a rear elevation view thereof.
